US00D767521S

(12) **United States Design Patent** (10) **Patent No.:** **US D767,521 S**
(45) **Date of Patent:** **** Sep. 27, 2016**

(54) **CELLULAR PHONE**

(71) Applicant: **LG ELECTRONICS INC.**, Seoul (KR)

(72) Inventors: **Joungyoung Joung**, Seoul (KR); **Hyunwoo Kim**, Seoul (KR); **Joonhyung Kim**, Seoul (KR); **Min Kim**, Seoul (KR)

(73) Assignee: **LG Electronics Inc.**, Seoul (KR)

(**) Term: **14 Years**

(21) Appl. No.: **29/501,695**

(22) Filed: **Sep. 8, 2014**

(30) **Foreign Application Priority Data**

Mar. 14, 2014 (KR) 30-2014-0012864

(51) **LOC (10) Cl.** **14-03**

(52) **U.S. Cl.** ..... **USPC ..... D14/138 AD; D14/138 G**

(57) **CLAIM**

The ornamental design for a cellular phone, as shown and described.

DESCRIPTION

FIG. 1 is a front, right side, perspective view of a cellular phone showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front, right side, perspective view of the cellular phone, with the rear cover in a slid state;
FIG. 9 is a front view of the cellular phone, with the rear cover in a slid state;
FIG. 10 is a rear view of the cellular phone, with the rear cover in a slid state;
FIG. 11 is a left side view of the cellular phone, with the rear cover in a slid state;
FIG. 12 is a right side view of the cellular phone, with the rear cover in a slid state;
FIG. 13 is a top view of the cellular phone, with the rear cover in a slid state; and,
FIG. 14 is a bottom view of the cellular phone, with the rear cover in a slid state.
The broken lines that are immediately adjacent to the claim, and define unshaded regions, represent the bounds of the claim, while all other broken lines are directed to environment; the broken lines form no part of the claimed design.

1 Claim, 12 Drawing Sheets
